BAROMETRIC DRAFT CONTROL

Edward B. Moore, Kankakee, Ill., assignor to
Sears, Roebuck and Co., Chicago, Ill., a corpora-
tion of New York

Application July 26, 1946, Serial No. 686,507

6 Claims. (Cl. 236—45)

1

My invention relates to barometric draft controls and has for a particular object provision of a draft control which may be manually adjusted so that it will automatically control the draft for a variety of conditions.

Barometric draft controls of this general nature are well known and consist of a pivoted plate or the like arranged in a flue or stack so as to be acted upon by the negative pressure within the stack and thus to vary the opening of the damper to meet the existing draft conditions and compensate automatically for changes in outside temperatures and wind conditions. However, it is desirable that a barometric damper may be manually adjusted so that an operator may set his draft at any desired intensity. An object of my invention is to provide such a manually adjustable barometric damper, which will maintain itself at a given setting within narrow limits.

Another object of my invention is to provide a device of the type referred to which will be simple in construction, inexpensive to fabricate and convenient to adjust.

Various other objects and advantages may suggest themselves as the description proceeds.

Referring now to the drawings forming a part of the specification and illustrating a preferred embodiment of my invention:

Fig. 1 is an elevational view showing a furnace and stack with a control device embodying my invention mounted in the latter;

Fig. 2 is an elevational view of the damper itself on an enlarged scale;

Fig. 3 is a fragmentary sectional view substantially along the line 3—3 of Fig. 2;

Fig. 4 is a top plan view of the same, partly in section; and

Figure 5 is a fragmentary sectional view substantially along the line 5—5 of Figure 2.

The numeral 10 indicates a conventional heating furnace which may be of the warm air or other desired type and having a flue 12 connected thereto. Arranged in the flue is a damper section 13 having a neck 15 extending laterally substantially at right angles to the major portion of the flue 12.

Secured in the neck 15 is an annular collar 16 having integral therewith an annular flange 17. Rotatably mounted in the flange 17 and retained by ears 40 is a cast ring 20 which may be provided on part of its periphery with teeth 22. These teeth are adapted to engage with a pinion 25 journaled in a plate 26 mounted above the collar 16 and preferably integral therewith. The pinion 25 is provided with a boss 28 which re-

2

tains a manually operable knob 30 similar to a radio tuning knob.

Secured to the ring 20 is a pivot rod 32 hingedly mounting a circular damper plate 35 of a diameter substantially corresponding to the inner diameter of the ring 20. The plate 35 may be attached to the pivot rod by any suitable means as for example by punching and forming the plate at 36 to provide integral hinge portions 37. A weighting disc 38 may be secured to plate 35 as by soldering or welding.

It will be seen that the hinge pin 32 is so placed as to divide the damper plate 35 into a major segment A and a minor segment B. Creation of a vacuum within the flue 12 will cause the major segment A to swing inwardly to an extent dependent on the amount of vacuum.

Should it be desired to adjust the damper, it may be manually rotated by knob 30 through the pinion and crank to a position where, instead of being balanced as in the position shown in Fig. 2, the major segment A will depend to a greater or less extent below the hinge pin 32. Obviously, when unbalanced, the vacuum will have to act upon greater gravitational effect than when the plate is balanced. Thus, a lower vacuum will effect as great a rotation in the balanced position as will a greater vacuum in the unbalanced position.

30 The gear and pinion arrangement permits adjustment with a minimum of effort.

Various changes may suggest themselves to those skilled in the art, and hence I do not wish to be limited to the specific forms shown or uses 35 mentioned, except to the extent indicated in the appended claims.

I claim:

1. In combination, means for controlling the draft in combustion apparatus comprising a circular damper, means for mounting said damper in a flue comprising a ring having peripheral teeth thereon, a hinge pivotally securing said damper to said ring, said hinge being offset from the center of said damper, a pinion cooperating with said teeth for rotating the damper in its own plane so as to shift the angular position of said hinge, and means for manually rotating said pinion.

2. Means for controlling the draft in combustion apparatus comprising a circular collar adapted to be inserted in a flue, a ring having a plurality of teeth thereon, said ring being rotatably mounted in said collar, a hinge pin eccentrically carried by said ring, a weighted damper plate 55 pivotally mounted on said hinge pin, a pinion

operatively connected to said ring, and means for manually rotating said pinion.

3. A combination as defined in claim 2 wherein said damper plate has a weight secured to the central portion thereof.

4. A combination as defined in claim 2 wherein said damper plate has a weight in the form of a disc secured substantially centrally thereto.

5. A combination as defined in claim 2 wherein the collar is relatively shallow in depth and has a plurality of spaced ears retaining said ring against outward displacement, said pinion being carried by a support carried by and extending radially from said collar.

6. Means for controlling the draft in combustion apparatus comprising a circular collar adapted to be inserted in a flue and formed to define

10

5

a channel, a ring journaled in said channel, a hinge pin eccentrically carried by said ring, a weighted damper plate pivotally mounted on said hinge pin, a rotary member bearing on said ring and offset radially therefrom, whereby said ring may be rotated in said channel, and a handle for actuating said rotary member.
